UNITED STATES PATENT OFFICE

CHARLES G. SMITH, OF MEDFORD, MASSACHUSETTS, ASSIGNOR TO RAYTHEON INC.,
OF CAMBRIDGE, MASSACHUSETTS, A CORPORATION OF MASSACHUSETTS

ELECTRON DEVICE

Application filed March 22, 1928. Serial No. 263,699.

My present invention relates generally to thermionic devices and in particular to the type which employs gas or vapor to facilitate conduction although not restricted to that type and has application to various uses such as amplification of electric current and detection of radio signals.

An object of my invention is to provide a new and improved tube structure of the type mentioned which is more efficient than those heretofore employed.

The novel features which I believe characteristic of my invention are set forth with particularity in the appended claims. The invention itself, however, both as to its organization and method of operation together with further objects and advantages thereof will best be understood by reference to the following description taken in connection with the accompanying drawing in which the figure represents a preferred embodiment.

As indicated on the drawing I employ a heater element 1 in the form of a filament, a cylindrical cathode 2, a control element 3 and an anode or plate electrode 4 of cylindrical form, concentrically arranged and all supported in the usual manner from the press of an envelope 5 from which the air has been completely excluded. The cathode consists of a thimble made of a material, refractory and having a relatively large heat capacity and practically surrounds the filament so that it may be heated readily by radiation. The thimble supports the lower end of the filament in the manner shown and provides a terminal therefor. The upper portion of the thimble is extended radially as a web or other conducting body, terminating in an intersticed member 6 which may be a helix, positioned between the control electrode 3 and anode 4.

For reason stated hereinafter, the distance between the member 6 and anode should be relatively small. The control electrode 3 may take any form but I find it desirable to give it a shape conforming to that of member 6 i. e. helical. In order to facilitate conduction, a vapor or an inert gas may be present within the envelope at a relatively low pressure; caesium vapor at a pressure approxi-

mately 10^{-5} mm. Hg has given satisfactory results and may be admitted by heating capsule 7 which contains suitable chemical e. g. caesium chloride and calcium chips. By spacing the portion 6 of the cathode a relatively short distance away from the plate 4, ionization by collision of electrons with caesium molecules is minimized. The theory upon which this is based is set out in my Patent 1,545,207 granted July 7, 1925, and later 60 patents.

In operation, the electrodes are connected to input and output circuits in the usual manner for signal amplification or detection, except that an additional lead is provided for the upper end of the filament which may be energized by alternating or direct current of suitable voltage; when alternating current is utilized, the metal content of the thimble is sufficient to maintain a substantially constant 70 temperature during the whole of the alternating current cycle. Emanations from the filament render the thimble portion 2 of the cathode electronically active which then takes on the function of a cathode. If desired, the 75 thimble may be treated with material designed to increase electron emission e. g. by coating with alkaline earth metal oxide or intermixing same with the metal content; although if caesium is employed for the vapor 80 it will inevitably settle upon all the metal parts of the tube including the outer surface of the thimble and suffice for this purpose. The position of the thimble is such that it 85 prevents the light radiation of filament from passing directly to the space bounded by the remaining electrodes, hence, photoionization of the conducting medium in the neighborhood of grid 3 is precluded, which is appreciable in the case of caesium, and the grid 90 remains unheated. This, in addition to the presence of the relatively short space between member 6 and the plate over which any appreciable voltage exists, enables the grid element to exercise a most effective control, in 95 fact, quite as much as in any ordinary electronic device. By placing a portion of the cathode member intermediate the grid and plate, feed-back and grid to plate capacity is diminished since the grid is shielded from 100

electrostatic action of the plate; the same shielding action also assures amplification greater than is ordinarily found in the usual type of tube.

5 I claim:

- 5 1. An electron discharge device comprising an evacuated envelope, a thermionically emitting cathode and an anode supported in said envelope, a control grid between said cathode and said anode, and an additional grid conductively connected to and mechanically supported by said cathode between said control grid and said anode.
- 10 2. An electron discharge device comprising an evacuated envelope, a pair of tubular electrode members surrounding each other within said envelope, means supporting one of said members in the envelope, means mechanically supporting the other of said members from said first member, an anode in said envelope, one of said members constituting an electron-emitting cathode, the other of said members having perforations to permit passage of electrons therethrough to said anode, and a control grid between said two members.
- 15 3. An electron discharge device comprising an evacuated envelope, a tubular cathode member supported in said envelope, a grid surrounding said cathode and carried thereby, said grid being conductively connected to said cathode, an anode surrounding said grid, an additional control grid interposed between said first grid and said cathode, and an incandescent heater inside said tubular cathode member, said cathode member being positioned to screen the space between said cathode and said anode from irradiation by said incandescent member.
- 20 4. An electron discharge device comprising an evacuated envelope, a tubular cathode supported in said envelope, a grid surrounding said cathode and connected thereto, an anode surrounding said grid, a control grid interposed between said first grid and said cathode, an easily ionizable gas filling in said envelope, and an incandescent heater inside said cathode, said cathode being positioned to protect the gas filling in the discharge space from ionization through irradiation by said incandescent heater, the spacing between said first grid and said anode being short to substantially reduce ionization of gas molecules by electrons moving through the space under the action of the field between the anode and the cathode.
- 25 5. An electron discharge device comprising an evacuated envelope, a relatively large-surface cathode member, an anode facing one side of said cathode, a protective grid interposed between said cathode and said anode, said grid being electrically connected to said cathode, a control grid between said protective grid and said cathode, an easily ionizable gas filling in said envelope, and an incandescent heating element adjacent said cathode for

heating the same to a temperature of electron emission, said cathode being mounted relatively to said heating element to protect the gas filling in the discharge space between said cathode and said anode from being ionized by 70 irradiation from said heater, the spacing between said protective grid and said anode being short to substantially reduce ionization of gas by collision with electrons moving through the discharge space under the action 75 of the field between the anode and the cathode.

In testimony whereof, I have signed my name to this specification.

CHARLES G. SMITH.
